Ivan Sors and Aladar Abrahamson,
New York, N. Y.

Application July 11, 1949, Serial No. 3,832

Term of patent 3½ years

(Cl. D57—1)

To all whom it may concern:

Be it known that we, Ivan Sors and Aladar Abrahamson, both citizens of the United States, residing at city, county, and State of New York, and New York city, county of Bronx, and State of New York, respectively, have invented a new, original, and ornamental Design for Sun Shield or Similar Article, of which the following is a specification, reference being had to the accompanying drawing, forming part thereof.

In the drawing

Fig. 1 is a rear perspective view of a sun shield showing our new design, the broken lines being for illustrative purposes only;

Fig. 2 is a rear perspective view of the sun shield alone; and

Fig. 3 is a bottom perspective view of the same.

We claim:

The ornamental design for a sun shield or similar article, as shown and described.

IVAN SORS.
ALADAR ABRAHAMSON.
